UNITED STATES PATENT OFFICE

PHILIP E. YOUNG, OF FAIRHAVEN, MASSACHUSETTS

DESIGN FOR A RUBBER SHOE

Application filed July 21, 1931. Serial No. 40,611. Term of patent 7 years.

To all whom it may concern:

Be it known that I, PHILIP E. YOUNG, a citizen of the United States, residing at Fairhaven, Massachusetts, have invented a new, original, and ornamental Design for a Rubber Shoe, of which the following is a specification, reference being had to the accompanying drawings, forming part thereof.

Fig. 1 is a plan view of a shoe showing my new design, and Fig. 2 is a side view thereof.

The stippling dividing the surface of the shoe into sun-ray bands is not intended to indicate a different color, but is intended to indicate stripes or bands which are alternately smooth and rough, and separated by very small ridges.

I claim:

The ornamental design for a rubber shoe as shown and described.

PHILIP E. YOUNG.
